To all whom it may concern:

Be it known that I, Sol Weinberg, a citizen of the United States of America, residing in New York city, county of New York, and State of New York, have invented a new, original, and ornamental Design for a Textile Fabric, of which the following is a specification, reference being had to the accompanying drawing, forming part thereof, wherein, the figure is a plan view of a textile fabric, showing my new design.

My design is composed of alternatingly contrasting groups of three contrasting sinuous stripes, said stripes being separated from each other by continuous sinuous lines of dots comprising alternatingly contrasting groups of four which lie in the troughs of the stripes having the same color. A corresponding group of four dots lies in the troughs of each outside stripe and corresponds in color thereto, all as shown against a contrasting background.

I claim:

The ornamental design for a textile fabric, substantially as shown and described.
